CLAIM

What is claimed is an ornamental design for a hub with stand for a mini computer, as shown and described.

DESCRIPTION

FIG. 1 is a front, top, left perspective view of a hub with stand for a mini computer showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

Wherein the broken lines depict portions of the hub with stand for mini computer hat form no part of the claimed design.
